D-777
Samuel H. Vance, New York.

Design for a Chandelier or pendant

Patented April 8-1856.

Fig. 1

Samuel B. H. Vance, of New York, N. Y.

Assignor to

Mitchell, Bliley & Co. of Connecticut.

Letters Patent No 777. Dated April 8. 1856

uuuuuu

The schedule referred to in these Letters Patent, and
making part of the same.

uuuuuu

To all whom it may concern:

Be it known that I, Samuel B. ^{H.} Vance
of the City, County and State of New York, have invented
an ornamental fixture, which is intended as a chanda-
lier or pendant, the configuration of which and the
ornaments thereon, constitute a new and original design;
And I do hereby declare that the following is a full and
exact description thereof, reference being had to the accom-
panying drawing, and to the letters of reference marked
thereon, which make a part of this specification.

My fixture is so constructed as to be easily
modified, and adapted to the use of gas, oil or any
other illuminating material.

Fig. 1. is a view of the chandelier with two branches.

In Fig. 1. A, is a socket screwed upon the top of
the tubing rod C, and by which the fixture is suspended.

Wes 777

B, is a round ornament directly under the socket A.

D, is an ornament composed of three leaves, and attached to and surrounding the tubing rod C. E, is an ornament in the shape of a tassel which is also attached to and surrounds the tubing rod C. F, F, F, F, are two branches curved and interwoven as shown in the drawing, on the outer ends of which are ornamented nozzles to which may be attached gas-burners or sockets for candles or lamps, as shown at H, H. I, is an ornamented handle suspended from the tubing branches by an ornamental ring, as at g, all as shown in this figure.

What I claim as my invention, and desire to secure by Letters Patent, is the design, configuration, and arrangement of the several parts and ornaments as herein set forth, forming a new and original design for a Chandlier or Pendant, with two branches or burners.
